UNITED STATES PATENT OFFICE.

CHRISTIAN WILDRICK, OF DES MOINES, IOWA.

CABINET IRONING BOARD.

Application filed November 10, 1921. Serial No. 514,271.

To all whom it may concern:

Be it known that I, CHRISTIAN WILDRICK, a citizen of the United States, and a resident of Des Moines, in the county of Polk and State of Iowa, have invented a certain new and useful Cabinet Ironing Board, of which the following is a specification.

The object of my invention is to provide a cabinet ironing board of simple, durable 10 and comparatively inexpensive construction.

More particularly, my invention relates to a peculiar type of mounting, especially adapted for supporting an ironing board member, whereby a great portion of the ironing board is entirely independent of any support, so as to make it easily used when ironing dresses or other such articles, which are ordinarily slipped over the end 20 of the ironing board.

Still a further object is to provide a yoke device, which is pivotally mounted, and which yoke device has the ironing board pivotally secured thereto, so that the ironing board may be moved pivotally relative to the yoke and the yoke device and ironing board may be pivotally moved together.

Still a further object is to arrange the parts so that when the ironing board is moved to inoperative position, that is in a vertical position, it will be received in a cabinet and remain in its vertical position or inoperative position without the aid of any catch devices.

With these and other objects in view, my invention consists in the construction, arrangement and combination of the various parts of my device, whereby the objects contemplated are attained, as hereinafter 35 more fully set forth, pointed out in my claim and illustrated in the accompanying drawings, in which:

Figure 1 is a perspective view of a cabinet with my improved ironing board shown in operative position.

Figure 2 is a sectional view taken on the line 2—2 of Figure 1, showing the arrangement of the cabinet relative to the wall of a building.

Figure 3 is a central, vertical, sectional view taken on the line 3—3 of Figure 2.

Figure 4 is a sectional view taken through the cabinet, which receives the ironing board member, the ironing board member being shown in inoperative position; and

Figure 5 is a front elevation of the ironing board, parts being broken away to better illustrate the construction.

In the accompanying drawings, I have used the reference numeral 10 to indicate generally a casing, which includes a pair of sides and a back 11. A hinged door member 12 is secured to the casing 10 and completes it. The casing 10 may be set in the 65 wall 13 of a building.

In order to support an ironing board member, I provide a cross bar 14 within the casing 10. The sides of the casing 10 are provided with recesses 15, which receive 70 the ends of the cross bar 14. The cross bar 14 may also be secured to the casing by the use of screws 16. However, the main support of the cross bar 14 is the 75 sides of the casing 10.

The cross bar 14 is provided with a longitudinal groove 17 in its under side and with an inclined surface 18, as clearly illustrated in Figures 3 and 4 of the drawings. The purpose of the groove 17 will 80 hereafter more fully be set forth.

Secured to the sides of the casing 10 are a pair of short angle bars 19, which have one of their sides extended back of the sides of the casing 10. The angle bars 85 are also secured to the sides of the casing 10 by means of the screws 20.

Pivotally mounted within openings formed in the angle bars is a yoke device A. The yoke device A consists of a pair 90 of arms 21 connected together at their outer ends by a cross piece 22. The upper ends of the arms 21 are bent at right angles and outwardly from the arms 21, so as to form trunnions 23, which are received in the 95 angle bars 19.

It will be seen that the yoke device A is pivotally mounted. Secured to the cross piece 22 and resting thereon is an ironing board member 24. The ironing board member 24 has its outer end slightly tapered as clearly shown in Figure 1. The ironing board member 24 is of the size and shape of an ordinary ironing board.

Placed on the under side of the ironing board member 24 and secured thereto is a thin slat 25, which is provided with a groove 26 running lengthwise of the slat. The groove 26 is designed to receive the cross piece 22 of the yoke device A.

From the construction of the parts just described, it will be seen that when the

slat 25 is secured to the ironing board member it rests over the cross piece 22, so as to pivotally connect the ironing board member relative to the yoke device. This is clearly illustrated in Figure 2 of the drawings.

A pair of short angle bars 27 have the cross piece 22 of the yoke device A extended therethrough. The pair of angle bars 27 rest against the side of the ironing board member 24 and also receive the ends of the slat 25. The angle bars 27 being secured to the ironing board member 24 to the slat 25 and also receiving the yoke device A form a very rigid construction.

In order to support the ironing board when it is in its horizontal or operative position and to retain it in that position, it is necessary for the inner end of the ironing board member 24 to rest against the under side of the cross bar 14. I provide a strip 28, which is a shape in cross section of the groove 17 in the cross bar 14. When the ironing board member is swung to its operative position, the strip 28 is received in the groove 17. This prevents any further pivotal movement of the ironing board relative to the yoke device A.

The arms 21 of the yoke device then support the ironing board member 24.

It will be understood that any weight applied to the ironing board is always applied to the upper surface thereof and near the outer end, so that the cross piece 22 of the yoke device forms a fixed pivotal point upon which the ironing board may swing. However, the cross bar 14 limits the pivotal movement and therefore retains the ironing board in its proper operative position.

The end of the ironing board and strip 28 are slightly beveled so as to conform to the beveled surface 18 of the cross bar 14.

I provide a pair of guide strips 29 which are fixed to the back side 11 of the casing near the lower ends thereof. The upper portions of the guide strips 29 are beveled as at 30. When the ironing board is in its vertical or inoperative position, the strip 28 rests against the guide strips 29, due to the fact that the ironing board is then suspended and supported only by the yoke device A.

The parts when in their inoperative position will remain in that position without the assistance of any catch devices or the like.

It will be seen that in order to lower the ironing board to operative position, it is necessary to only pull the ironing board

towards you. The ironing board may then be swung upon the yoke device as its pivot.

It may properly be said that the ironing board swings upon two pivots. It first swings upon the yoke device as one pivot, while the yoke device and the ironing board swings upon the pivot point of the yoke device, which is in the angle bars 19.

It will be seen that I have provided a mounting for an ironing board, which engages the ironing board at one end thereof, so that a great portion of the ironing board is free from any supports, whereby it can more easily be used for the ironing of a great many articles.

It will also be seen that I have provided an ironing board, which may be folded, and which when folded will occupy a minimum amount of space, due to the fact that there are no legs or other supports, which engage the floor, connected with the ironing board.

Some changes may be made in the arrangement and construction of the various parts of my device, without departing from the essential features and purposes of my invention, and it is my intention to cover by my claim, any modified forms of structure or use of mechanical equivalents, which may be reasonably included within its scope.

I claim as my invention:

In an ironing board, a frame, a cross bar on the frame having a groove in its under surface, an ironing board, a yoke having a portion pivotally mounted under the ironing board, a cleat secured to the end of the ironing board on its upper surface and adapted to be received in the cross bar groove, the ends of the yoke device being pivoted to the frame at a point substantially above the cross bar, whereby the yoke may serve as a suspending brace when the ironing board is in horizontal position, and whereby the ironing board may be swung around the yoke and the yoke swung downwardly with relation to the frame, to bring the parts into position where the ironing board will be suspended by the yoke in vertical position and a pair of guide members adapted to coact with the cleat for holding the lower end of the ironing board away from the back of the frame, the upper ends of the guide members having tapered surfaces ending flush with the rear face of the cross bar slot for guiding the cleat into the slot.

Des Moines, Iowa, November 7, 1921.

CHRISTIAN WILDRICK.
